UNITED STATES PATENT OFFICE

JOHN E. BELL, DECEASED, LATE OF BROOKLYN, NEW YORK, BY LOLA R. BELL, EXECUTRIX, OF BROOKLYN, NEW YORK, ASSIGNOR TO SINCLAIR REFINING COMPANY, OF NEW YORK, N. Y., A CORPORATION OF MAINE

APPARATUS FOR CONDENSING HYDROCARBON VAPORS

Application filed January 22, 1925. Serial No. 3,986.

This invention relates to an improved apparatus for condensing the vapors and cooling the condensed distillates from stills in which hydrocarbon oils are subjected to distillation.

In condensing and cooling the vapors and distillates from oil stills, heat is abstracted from the hot vapors escaping from the still to cool and to condense the distilled vapors, and heat is further abstracted from the condensed distillate to cool it to a final temperature below the temperature of condensation. The distilled products escaping from oil stills always include, although in varying amount, some fixed gases. In the methods hitherto generally employed, the sensible heat of cooling water has been used to effect the cooling and condensation of the oil vapors, and the cooling and condensing operation has been carried out in a single receptacle so that as condensate formed further cooling and condensation involved heat transfer to a mixture of vapors, liquids and gases. Due to the presence of fixed gases, even the final cooling of the condensed distillate is commonly carried out while the distillate is admixed with gases, but there are several difficulties incident to the transfer of heat from such mixtures as well as mechanical difficulties involved in handling such mixtures. In the methods hitherto used, it has been necessary to discharge the cooling water from the condenser at relatively low temperature and to employ relatively large volumes of cooling water to maintain the desired low final temperature. Moreover, the cooling of the condensed distillate to the desired final temperature is usually the factor controlling the amount of cooling water employed and the amount of heat transferring surface required, so that it has been impossible to realize the full benefit from other economies effected in cooling and condensing the vapors; and even where the temperature of the vapors entering the condenser has been lowered it has not been possible to obtain an entirely corresponding decrease in the amount of cooling water employed due to the fact that the temperature difference between the vapors and cooling water is also

reduced so that the heat transfer is thereby retarded.

Among the objects of the present invention are to provide an improved apparatus for condensing and cooling the vapors and distillates from oil stills in which the difficulties incident to the absorption of heat from mixtures of gases, vapors and liquids, or of gases and liquids are overcome or minimized, in which an improvement in the economy of cooling water employed is effected without sacrifice as to the final temperature of the condensed distillate, and which enables full advantage to be taken of improvements in the general efficiency and economy of the cooling and condensing operation when practiced in conjunction with methods or in apparatus in which an initial cooling of the vapors from the still is effected before they enter the condenser proper.

According to the present invention, the oil vapors from the still are cooled and condensed, the fixed gases and condensed distillate are then separated, and the separated condensed distillate is subjected to a further cooling operation after separation of the fixed gases, whereby the efficiency and economy of the combined cooling and condensing operations are increased. The vapors may also be subjected to a preliminary cooling before they are subjected to the cooling and condensation treatment.

In one way of operating the apparatus of the invention, the hot vapors from the still are first cooled and condensed by heat exchange with cooling water, the fixed gases and condensed distillate are then separated, the separated condensed distillate is then brought in heat exchanging relation with cooling water, and cooling water is passed from the second cooling operation to the first cooling and condensing operation. The condensed distillate is thereby cooled to the desired final temperature in an improved way, while the water discharged from this cooling operation is available at a temperature suitable for use as a cooling medium in the first cooling and condensing operation. A lower final temperature of the condensed distillate may thus be obtained with

- the same amount of cooling water or the same final temperature may be obtained with a reduced amount of cooling water, while at the same time the burden of cooling the condensed distillate to the desired final temperature is removed, in large part, from the main condenser so that less cooling water may be employed therein. Due to the increased efficiency of the operation of cooling the condensed distillate when it is carried out subsequent to separation of the fixed gases, a marked economy in overall consumption of water may be obtained. The main cooling and condensing of the hot vapors from the still may be carried out in much the usual way, and in a condenser of ordinary construction, although the amount of cooling water employed and the size of the condenser may be materially reduced.
- It is advantageous to employ all of the cooling water in the second cooling treatment and to employ all of the cooling water discharged from the second cooling treatment in the first cooling and condensing operation as in this way the maximum cooling and condensation is secured in both stages of the combined operation. Where all of the cooling water is first employed in cooling the separated condensed distillate to the desired final temperature and then for cooling and condensing the hot vapors from the still, the amount of cooling water may be regulated to control the final temperature of the condensed distillate and, in all ordinary cases, this will provide more than enough cooling water to carry out the cooling and condensing operation in the condenser proper. A supplementary amount of cooling water may, however, be supplied to either the second cooling operation, the first cooling and condensing operation, or to both operations.
- The apparatus of the present invention is of special value and application when employed in conjunction with an improved method and apparatus described in an application filed October 29, 1924, Serial No. 746,471. The potential economy thereby made available due to the reduced temperature of the vapors entering the condenser can thus be more fully realized and a further improvement in efficiency and economy obtained. In such a combined operation, a saving of as much as 50% or more may be effected with respect to the cooling water used.
- The apparatus of the present invention comprises a still, which may or may not be provided with a reflux or fractionating tower, a condenser communicating with the vapor space of the still or with the reflux tower and arranged to discharge into a separator, and a cooler connected to the separator so that the condensed distillate is discharged therethrough. The cooler may advantageously take the form of a tubular heat exchanger, arranged for circulation of the condensed dis-
- tillate through the tubes and for circulation of the cooling water through a jacket about the tubes. The condenser may be of conventional construction and arrangement although a considerably smaller condenser may be employed. Connections are provided to conduct cooling water first through the cooler and then through the condenser. The apparatus of the invention may also include an evaporative cooler, or condenser, arranged between the main condenser and the still or reflux tower so that the hot vapors from the still first pass therethrough before they enter the condenser proper. Connections may be provided for introducing water to the evaporative condenser either from the main condenser or from a separate source.
- The apparatus of the present invention may be employed in condensing the vapors and cooling the distillates from pressure stills. Where so employed, the still pressure may be regulated and reduced between the still and condenser, between the condenser and the cooler, or beyond the cooler and separator. Where an evaporative condenser is also employed, the still pressure likewise may be regulated and reduced between the evaporative condenser and the still or between the evaporative condenser and the main condenser. It is, however, advantageous to maintain the same pressure on the condensed distillate as is maintained on the condenser to a point beyond the separator, but the pressure on the condensed distillate may then be reduced either before it enters or after it leaves the cooler.
- The invention will be further described in connection with the accompanying drawings illustrating, somewhat diagrammatically and conventionally, apparatus embodying the invention, but it will be understood that the invention is exemplified by this further description and illustration and is not limited thereto.
- In the accompanying drawings:
- Fig. 1 represents in elevation and partly in section a still, condenser and cooler, and Fig. 2 similarly represents a still, evaporative condenser, main condenser and cooler.
- The still illustrated in the drawing is of the direct fire heated type and comprises a shell 1 arranged over a setting 2. Arranged above the still shell is a reflux tower 3. The reflux tower illustrated is of the general construction and operation described in a prior application filed April 1, 1924, Serial No. 703,338. The still is provided with a charging line 4, and connection 5 is arranged at the upper end of the tower for introducing feed into the still through the tower. The vapors escape from the top of the tower through vapor connections 6.
- Referring to Fig. 1, the vapors escaping from the tower on the still enter the condenser through connection 7. In the con-

denser, the vapors, and condensate as it is formed, flow downwardly through a series of pipe coils 8 in indirect heat exchanging relation with cooling water in which they are immersed in the condenser box 9. Cooling water enters the condensing box through connection 10 and overflows therefrom through connection 11.

The condenser illustrated is the pipe coil type in general use in oil refining. In such a condenser, the condensate as formed collects in the lower part of the condensing pipes and flows as a trickling stream therethrough to the discharge outlet. It will be apparent that the area of heat transfer to the condensate is relatively small as compared to the area of heat transfer to the uncondensed vapors and gases and this renders the condenser structure illustrated inefficient as a cooler of the condensate. In the way in which such condensers are ordinarily employed, they are required to condense the vapors and also to cool the condensate, and therein efficiency in this latter function renders the entire operation inefficient, particularly as compared to the apparatus of the present invention in which these functions are separated to an extent whereby a marked increase in efficiency is obtained. In the apparatus of the present invention, the vapors are condensed and are cooled after separation from the fixed gases, whereby the efficiency of the entire operation is improved, as will appear from the continuing description.

From the condenser, the condensed distillate and admixed gases are discharged into a separator 12, the fixed gases being discharged upwardly therefrom through connection 13 and the condensate downwardly through connection 14. The condensate flows through connection 14 to and through the cooler 15 where it is passed in indirect heat exchanging relation with cooling water and from which the cooled condensed distillate escapes to a run-down tank or other receiver through connection 16. Cooling water is supplied to the cooler through connections 17 and 18 and the cooling water discharged from the cooler is circulated to the condenser box through connections 19 and 10. A by-pass connection 20 is provided for supplying cooling water directly to the condenser and a connection 21 for discharging cooling water from the cooler without passing it to the condenser.

In operation, the hot vapors are cooled to the condensation temperature and are condensed in the condenser and the resulting mixture of condensate and fixed gases is then separated. The fixed gases escaping may also include some small amount of uncondensed very light vapors which may be recovered in suitable recovery apparatus. The separated condensed distillate is discharged from the separator at a temperature somewhat above

the desired final temperature but is brought to the desired final temperature by further cooling treatment in the cooler. The cooling water employed in the cooler is heated to a temperature somewhat higher than its initial temperature, approaching that of the condensed distillate entering the cooler but below the temperature of condensation, and is then employed in the main condenser to cool and condense the hot vapors from the still. In general, all of the cooling water is first passed to the cooler and then to the condenser and the flow of cooling water is regulated to control the final temperature of the condensed distillate as it escapes from the cooler. Additional cooling water may, however, be supplied either to the condenser or to the cooler, or to both.

Referring to Fig. 2, the vapors escaping from the tower on the still enter the evaporative condenser through connection 6. In the evaporative condenser, the vapors enter headers 25 from which they flow through horizontal tubes 26 and 27 and the return header 28 to headers 29 from which they are discharged from connection 30 to the condenser proper. The headers 25, 28 and 29 and the horizontal tubes 26 and 27 are arranged within a receptacle 31 adapted to contain a relatively small body of water submerging, or almost submerging, the tubes 26 and 27. The tubes 26 and 27 may be provided with flanges or a series of annular rings or may consist of special elements for increasing the amount of heat transferring surface. Water vapor liberated within the receptacle 31 escapes upwardly through the stack 32, and openings 33 provided with dampers 34 are arranged in the upper part of the receptacle above the normal liquid level to permit a regulated draft of air to be drawn in over the surface of the water by the escape of steam through the stack to promote vaporization of the water.

In the condenser proper, the partially cooled vapors from the evaporative condenser, together with any condensate produced therein, flow downwardly through a series of pipe coils 8^a in indirect heat exchanging relation with the cooling water in which they are immersed in a condenser box 9^a; and from the condenser the condensed distillate and admixed gases are discharged into a separator 12^a, the fixed gases being discharged upwardly therefrom through the connection 13^a and the condensate downwardly through connection 14^a. The separated condensate flows through connection 14^a to and through the cooler 15^a and the cooled condensed distillate escapes from the cooler through connection 16^a.

Cooling water is supplied through connection 17^a and after passing through connection 18^a and the cooler 15^a is circulated to the condenser box through connections 19^a

and 10^a. Additional cooling water may be supplied to the condenser box through connections 20^a and part of the water circulated through the cooler may be discharged through connection 21^a. The cooling water overflows from the condenser box through connection 11^a. A pump 35 is arranged to withdraw a part of the water escaping through connection 11^a and to introduce it through connections 36 into the receptacle 31 in which the cooling tubes 26 and 27 are arranged. A connection 37 is also provided to discharge any excess water from the receptacle 31 into the waste connection 11^a.

15 In operation, the water level in the receptacle 31 is maintained at the approximate elevation of the top of the tubes 26 and water is supplied to the evaporative condenser through the connection 36 at a rate just sufficient to maintain the level in the receptacle 31 as the water is evaporated with the minimum of overflow therefrom necessary for practical control. Sufficient cooling water is circulated through the cooler 15^a to cool the 20 condensed distillate to the desired final temperature and sufficient cooling water is supplied to the condenser 9^a to condense the vapors from the still. Advantageously, all of the cooling water employed is circulated first 25 through the cooler 15^a and then through the condenser 9^a, and part of the water from the condenser 9^a is employed in the evaporative condenser. Additional cooling water may, however, be supplied to either operation to 30 regulate the cooling or the condensation.

35 The hot vapors from the still first pass through the tubes 26 and 27 and cause evaporation of the relatively small volume of water maintained in the receptacle 31 and are thereby partially cooled. Heavier constituents of the vapors boiling above the boiling point of water may also be condensed in whole or in part. The partially cooled vapors then enter the condenser proper where they are 40 condensed, and after separation of the fixed gases, the condensed distillate is cooled to the desired final temperature in the cooler 15^a. A large part of the cooling of the condensate is thus carried on after the separation of fixed 45 gases when it can be carried out more efficiently due to the absence of the fixed gases while the temperature of the vapors entering the condenser is also reduced, and by removing the major burden of cooling the condensed distillate from the condenser proper 50 in this way a further improvement in the efficiency of the operation following is secured.

55 The vapors escaping from an oil still comprise a mixture of constituents of various boiling points, and condensation, or vaporization, of the different constituents takes place over a range of temperature rather than at a single definite temperature. Different constituents also have different specific heats

as vapors and liquids and different heats of vaporization. These factors may vary the saving of cooling water which can be effected in any given case.

It will be apparent that the present invention provides an improved apparatus for condensing and cooling oil vapors and distillates in which the vapors from the still are first cooled and condensed by heat exchange with cooling water and are then further cooled after separation of fixed gases and in which cooling water is employed first in the cooling operation and then in the cooling and condensing operation to which the vapors are first submitted. In cooling and condensing light fractions of low average boiling point the temperature at which the distilled products are discharged from the condenser proper must be maintained at a correspondingly low point to insure effective condensation of all of the light constituents. With heavier fractions of higher average boiling point, however, the distilled products may be discharged from the condenser proper at a correspondingly increased temperature and a greater proportion of the cooling effected in the after cooler.

It will also be apparent that the present invention provides an improved apparatus for condensing and cooling oil vapors and distillates in which the vapors from the still are first partly cooled, and in some cases partly condensed, by vaporizing a relatively small body of water, then further condensed by giving up additional heat to a relatively large body of water as sensible heat, followed by cooling of the condensate after separation of the fixed gases. In the evaporative condenser, the temperature of the vapors may be reduced to a temperature somewhat above and approaching the temperature of water, and the amount of heat which can be extracted from the vapors by vaporizing water in the evaporative condenser varies with the character of the distillate as well as with the temperature of the vapors escaping from the still, heavier vapors and hotter vapors giving up a greater proportion of their heat therein. Where the condensation of the vapors and cooling of the condensed distillate is carried out in three stages in this way, the load on the condenser proper is reduced both by reducing the temperature at which the vapors enter the condenser and by relieving the condenser of the burden of cooling the condensate from the temperature of condensation to the desired final temperature.

What is claimed as new and desired to be secured by Letters Patent of the United States is:

1. In combination in an apparatus for condensing and cooling vapors and distillates from oil stills, a condenser and a cooler, connections therebetween including a separator

arranged to discharge liquid condensate to the cooler and to separate fixed gases, and means for supplying cooling water to the cooler and for supplying cooling water to the condenser from the cooler.

5 2. In combination in an apparatus for condensing and cooling vapors and distillates from oil stills, an evaporative cooler, a condenser and connections for passing vapors and gases from the evaporative cooler there-through, a separator communicating with the condenser, an after cooler and connections for passing liquid condensate from the separator through the cooler, and means for supplying water to the after cooler and for supplying water to the condenser from the after cooler.

10 3. In combination in an apparatus for condensing and cooling vapors and distillates from oil stills, an evaporative cooler, a condenser and connections for passing vapors and gases from the evaporative cooler there-through, a separator communicating with the condenser, an after cooler and connections for passing liquid condensate from the separator through the cooler, and means for bringing water successively into heat exchanging relation with the after cooler and the condenser and for supplying the evaporative cooler with water from the condenser.

15 30 In testimony whereof I affix my signature.
